MACHINE FOR CONVERTING AND SPRAYING MATERIALS

Joseph Lee Kelly, Union, and Frank J. Carragher,
Irvington, N. J.

Application April 21, 1953, Serial No. 350,159

4 Claims. (Cl. 299—86)

1

This invention relates to a machine for spraying materials. It has particular reference to a machine for coating surfaces with materials such as solid matter normally of comparatively sluggish consistency. The machine of this invention converts said matter to a relatively liquid, flowing state, and provides for controlled projection thereof by the operator onto the surface to be covered.

Pursuant to the invention, a casing is provided having a compartment from which the material to be sprayed passes through a flexible hose and spray gun. Pursuant to the invention, the material is heated by a second compartment and is kept heated right up to the point of discharge from the spray gun. The compartment into which the relatively solid matter is initially deposited is provided with pressure means and may be provided with a safety valve for the relief of pressure if it rises above a predetermined safe value. The second compartment, which serves the function of heating the first compartment, is filled with a heating medium such as oil, which is circulated through the flexible hose and up to the gun, from which point it is pumped back to the second compartment. An air line is preferably connected to the spray gun and kept at the heated temperature of the material in the first compartment; the air line, for that purpose, is passed through the second compartment immediately below the floor of the first compartment, thereby minimizing loss of heat in contact with the material passing through the spray gun under pressure.

These and other advantageous objects, which will appear from the drawings and from the description hereinafter, are accomplished by the structure of our invention, of which an embodiment is illustrated in the drawings. It will be apparent, from a consideration of said drawings and the following description, that the invention may be embodied in other forms suggested thereby, and such other forms as come within the scope of the appended claims are to be considered within the scope and purview of the instant invention.

In the drawings:

Fig. 1 is a partly fragmentary, elevational view of a machine for converting comparatively sluggish solid matter to a relatively liquid, flowing state of controlled projection, embodying the invention, and

Fig. 2 is an opposite side elevational view thereof, showing, fragmentarily, the spray gun and its connection with the casing.

2

As shown in the drawings, the machine of the invention is generally designated by the reference character 10 and comprises a casing 11 which is divided, as, for example, by the wall 12, into a first compartment 13 and a second compartment 14. The first compartment 13 is provided with a cap 15 or the like for filling it with the material to be sprayed. The latter may be a solid material of comparatively sluggish characteristics at normal temperature, which may be converted into a relatively smooth flowing liquid or may be thinned out and, therefore, made better adaptable for projection upon heating. The second compartment 14 is the heating compartment; it is located immediately below and contiguous to the first compartment. In the form shown in Figs. 1 and 2, the first and second compartments are divided by the wall 12 which is disposed interiorly axially and intermediate the height of the casing and coextensive therewith longitudinally and transversely. The second compartment 14 may be filled through a suitable filler pipe 16 or the like. By the arrangement described, the lower compartment may be filled with oil or the like which, in turn, may be heated by any suitable means, as, for example, by electric heating element 17 passing through the casing as at 18 and which may be connected exteriorly of the casing with a source of current by means of the cord 19 shown fragmentarily. A thermostat 43 may be cut into the circuit to heating element 17.

By the arrangement described, the contents of the first compartment 13 may be heated to the desired temperature for projection through a spray gun 20 having a control trigger 21 and nozzle 22 for projection of the material onto the surface to be covered thereby.

By the means above described, the second compartment 14 is a heating compartment for heating the first compartment 13 to thereby heat the matter therein and convert the same to a relatively liquid flowing state for projection through spray gun 20. Flexible line 23 is connected at one end 24 to the second compartment 14 and at the other end 25 to spray gun 20. A flexible return section 26 is provided between the spray gun 20 and the second compartment 14 and is connected to a pump 27 which in turn is connected by means such as shown as at 28, 28' to the second compartment. By this arrangement, the heated bath oil from the second compartment may be passed through flexible line 23 up to the point, viz: the spray gun, at which the material from compartment 13 is to be projected,

and is thence returned to the second compartment in a complete circuit. A flexible line 29 connected at opposite ends to the first compartment and to the interior of the spray gun, respectively, passes through the flexible line 23 so that the bath heating liquid of the second compartment will surround the line 29 for the material of the first compartment being moved to the spray gun, to maintain the same heated up to the point of passage. The device is provided with pressure means, such as, for example, compressed air line 35, connected as at 36 with a compressor or other external source of compressed air. The compressed air line passes through the wall 12 and into the second compartment, and is preferably passed transversely back and forth within the second compartment immediately beneath the first compartment, so that the air passing from the point of entry 35 through the machine, will be heated to the point 37 at which said air line leaves the casing for connection with flexible compressed air line section 37' leading to the spray gun 20. Intermediate the sections 37, 37' of the air line, a gauge 38 or the like may be provided to indicate the direct pressure to gun 20, and a gauge 40 may be provided to indicate the pressure in the first compartment 13. Valve 39 may be cut into the line 37 and its connection with the first compartment to regulate the pressure exerted on the material in compartment 13; said valve may be by-passed in the connection between the line 37 and line 37' to the spray gun 20 to give the latter the benefit of the full pressure of line 37. The first compartment may be provided with a safety valve 41 to automatically relieve any excess pressure. By the arrangement described, it will be noted that, pursuant to the invention, a highly effective and efficient means is provided for the conversion of the matter to be projected from a solid, comparatively sluggish state, to a relatively liquid flowing state and for the maintenance of the temperature thereof to the point of discharge thereof from the spray gun.

It is to be particularly observed that the machine or apparatus above described is self-contained and the casing 11 is provided with casters 42 whereby the apparatus is capable of being rolled into a relatively long vat whose interior wall is to be lined and then moved from the remote end of the vat to an opening therein in the course of a wall lining operation by the improved apparatus.

Having thus described our invention, what we claim as new and desire to secure by Letters Patent is:

1. Apparatus for converting comparatively sluggish, solid matter to a substantially liquid

flowing state and for the controlled projection thereof onto a surface to be covered thereby, comprising an elongated casing, a horizontally disposed partition wall in said casing dividing the same into upper and lower compartments, said casing being provided with a filling opening for admission of the said matter into said upper compartment, said casing being further provided with a second filling opening for the admission of fluid into said lower compartment, means supported by said casing and extending into said lower compartment for heating the fluid therein, a spray gun for controlling the projection of said matter onto said surface, a flexible conduit connecting said spray gun with said upper compartment, a second flexible conduit surrounding said first conduit and having one end thereof communicating with said lower compartment and the opposite end thereof connected to said spray gun for contact of heated fluid from said lower compartment with said first conduit for heating the flowing matter therein, a third conduit communicating with said second conduit extending from said spray gun to said lower compartment for return of the heating fluid thereto, a pump in said apparatus with which said third conduit is in communication for forced circulation of said heating fluid, and an air conduit extending through said lower compartment and to said spray gun for conducting compressed air to said gun for forced projection of the liquefied matter therefrom.

2. Apparatus according to claim 1, wherein said casing is provided with casters, and wherein said apparatus is a self-contained unit for movement within a vat in the progressive coating of the inner wall whereof from the remote end of the vat to an entrance opening therein.

3. Apparatus according to claim 1, wherein said air conduit is disposed beneath and adjacent said partition wall and wherein same is of serpentine formation.

4. Apparatus according to claim 1, together with an air conduit in communication with said first air conduit and which is in communication with said upper compartment, a pressure gauge in communication with said air conduits, and a safety valve in communication with said upper compartment.
